UNITED STATES PATENT OFFICE

FRANCIS JOSIAH BATTAMS, OF RHYL, WALES

BOW GUIDE

Application filed March 13, 1929, Serial No. 346,764, and in Great Britain March 16, 1928.

This invention relates to bow-guides for violins and similar stringed musical instruments which are played by means of a bow, and has among its objects to provide an improved and simplified construction of bow-guide of the kind adapted to be clipped to the finger-board and to provide a stop determining the extent to which the bow may be moved away from the bridge in playing.

It has before been proposed to provide a bow-guide of the kind referred to comprising a U-shaped piece of wood or the like arranged over the free end of the finger-board and clamped thereto by frictional engagement with the edges thereof.

According to the present invention, I provide a bow-guide comprising a spring clip portion having oppositely disposed curved or channelled parts adapted to extend around and to grip the respective lateral edges of the finger-board of the instrument and provided with a projection extending towards the bridge and forming a longitudinal guide or fence for the bow at right angles to the strings for the purpose of limiting the extent to which the bow may be moved away from the bridge in playing. Means such as a transversely extending bolt and nut may be provided if desired to cause the clip to engage the edges of the finger-board more firmly and thereby to render the attachment of the device more secure. Preferably the projecting part forming the guide comprises a strip of soft felt or equivalent material serving to protect the side or back of the bow or the hair thereof from damage.

In order that the present invention may be clearly understood and more readily carried into effect, it is hereinafter described with reference to the accompanying drawings, in which:—

Figure 1 is a perspective view of an improved bow-guide and tone-improver con-

structed in accordance with the present invention;

Figure 2 is an end elevation thereof showing same applied to the finger-board of an instrument;

Figures 3 and 4 show in end elevation and side elevation respectively a slightly modified form of device.

As shown and referring generally to the accompanying drawings, the improved bow-guide or fence and tone-improver in both forms comprises a substantially C-shaped or three-sided rectangular clip *a* of spring metal or other suitable or preferred material, which is adapted to be clipped over the edges of the finger board *b* of the instrument at its inner end so as to provide a longitudinal guide for the bow in a plane at right angles to the strings *c*. The clip *a* itself may conveniently be formed of spring band metal, such as steel, and it is provided at its free ends with inwardly directed open-sided loops *d* adapted to embrace or clip on the side edges of the aforesaid finger board *b*, thus as in the arrangement shown in Figures 3 and 4 enabling the guide or fence and tone improver to be sprung or clipped into position and rigidly retained in place by the tension of the springs alone. If preferred, however, I may provide a fastening bolt *e* and finger nut *f* to make the fixing more permanent and also to give a somewhat wider range of adjustment. I suitably secure to, or provide in connection with the clip a projecting strip *g* of soft felt or some equivalent material which will not damage the side or back of the bow or the hair thereof or cause disagreeable noises when contact is made therewith.

In the preferred construction shown in Figures 1 and 2 the clip *a* is formed with a fence portion *a*¹ of substantial dimensions which is also spaced somewhat in advance of the end of the finger board or towards the bridge of the instrument so as to ensure

play nearer the bridge if required and it is this fence portion *a'* which serves to carry the felt portion *g*. In the construction shown in Figures 3 and 4 the side of the clip itself forms the guide in conjunction with the projecting felt strip.

In use it is simply necessary to spring or clip the bow guide and tone improver on to the end of the finger board of the violin or other instrument with the projecting felt strip *g* directed towards the bridge, and then it can readily be seen whether the bow is being held correctly at right angles to the strings of the instrument and at a proper distance from the bridge as required, and this without any restraint on the free movement of the bow. In other words, the bow is free to be tilted about its own longitudinal axis as is required in order to produce the correct tone from the instrument, whilst in no way detracting from the value of the guide as an indicator of the position of the bow.

The guide and tone improver can be adjusted for use to any convenient position in relation to the finger-board enabling students to practise at slightly different distances from the bridge, which practise is essential to obtain the different graduations of tone.

The improved bow-guide will be found to be extremely useful not only to pupils when exercising or receiving instruction, but also to more experienced players for tonal effects.

35 What I claim is:—

1. A bow guide comprising a clip formed to engage the respective lateral edges of the finger-board of a stringed musical instrument having a finger-board and bridge, means whereby the edges of the clip may be moved toward one another to grip the finger-board, an extension from and rigid with the clip including a supporting portion disposed parallel to the bridge beyond the end of the finger-board when the clip is in place, and a flexible guide element carried by said supporting portion.

2. A bow guide comprising a clip formed to engage the respective lateral edges of the finger-board of a stringed musical instrument having a finger-board and bridge, means whereby the edges of the clip may be moved toward one another to grip the lateral edges of the finger-board, an extension from and rigid with the clip including a supporting portion disposed parallel to the bridge beyond the end of the finger-board when the clip is in place, and a flexible guide element carried by said supporting portion, said guide being extended laterally beyond the finger-board to insure accurate guiding of the bow during playing and maintaining the bow in close relation to the bridge.

65 3. A bow guide comprising a clip formed

to engage the respective lateral edges of the finger-board of a stringed musical instrument having a finger-board and bridge, means whereby the edges of the clip may be moved toward one another to grip the finger-board, an extension from and rigid with the clip including a supporting portion disposed parallel to the bridge beyond the end of the finger-board when the clip is in place, and a strip of felt carried by said supporting portion.

In testimony I have hereunto signed my name.

FRANCIS JOSIAH BATTAMS.
